UNITED STATES PATENT OFFICE.

FRED FEAR, OF NEW YORK, N. Y., ASSIGNOR TO J. H. DOXSEE & SONS, OF NEW YORK,
N. Y., A CORPORATION OF NEW YORK.

HYDRAULIC EXCAVATING AND HARVESTING APPARATUS.

Application filed March 31, 1920. Serial No. 370,085.

This invention is a hydraulic excavating apparatus, and it pertains, more particularly, to an excavator of that kind wherein a hydraulic current is employed in the operation of harvesting sub-aqueous products such as clams, oysters and the like.

The object of this invention is to conduct the operations of dislodging sub-aqueous products from their beds of propagation, and to transport the same, through the agency of a hydraulic current, and, further, to separate the products from the hydraulic current while permitting the latter to flow uninterruptedly, to the end that the collection of the products may be carried on economically and at the desired speed and without subjecting the operating parts to the possibility of injury by the products while in transit or while in the collective stage.

To these ends, my invention embodies a collecting chamber provided with a suction inlet and with a suction outlet, combined with a separating element positioned within said chamber and intermediate said suction inlet and the suction outlet, said chamber and the separating element cooperating for the hydraulic current to flow uninterruptedly through said chamber whereas the separating element acts primarily to detain the products within the chamber, whence the products may be removed at the desired time.

With this collecting chamber cooperates a hydraulic pumping mechanism and a suitable dredging conduit for the purpose of establishing the flow of a hydraulic current from the water bed whereon the marine growth is propagated, said hydraulic current being of sufficient capacity to effect the dislodgment of the products and to convey the same into the collecting chamber.

The invention embodies, also, means whereby the collected mass of products may be removed as required from the collecting chamber.

The invention embodies, further, means for priming the collecting chamber and the hydraulic pipe line in order to initially set the apparatus into action.

Other functions and advantages of the invention will appear from the following description taken in connection with the drawings, wherein—

55 Figure 1 is a view in side elevation illus-

trating graphically a hydraulic excavator according to this invention.

Figure 2 is a longitudinal section on an enlarged scale of the collecting chamber.

Figure 3 is a sectional plan view of the collecting chamber.

In order that others may understand my invention I have illustrated a conventional form of hydraulic dredge in Figure 1 of the drawings, wherein A designates a barge or scow upon which is mounted a hydraulic pump B and a suction pipe C, the latter being suitably supported at c for an inclined length c' of said pipe to dip into the water for a suitable depth in order to reach the bed devoted to the propagation of the products, such as clams, oysters, etc., which it is desired to harvest. The several parts may be of the construction usual in the art of hydraulic dredges, or they may be of any approved design or construction.

According to this invention, a collecting chamber D with a separator E are interposed in the line of the flow of a hydraulic current that is established and maintained in the suction pipe C by the operation of the hydraulic pump. As shown in Figures 2 and 3, said chamber is a closed tank, usually of metal and of a desired capacity, said tank being provided with a suction inlet d and a suction outlet d'.

The suction pipe C is attached to the tank in a suitable way for communication with the suction inlet d, whereas a pipe F is attached to the bottom of the tank for communication with the suction outlet d', said pipe F being connected to the hydraulic pump B and forming the intake to it.

The separator E is in the form of a grating positioned within the chamber and intermediate the suction inlet d and the suction outlet d', see Figure 2. As shown, the grating comprises two members e, e', one of which members e is inclined across the line of flow of the hydraulic current through the chamber, whereas the other member e' is horizontally positioned within the lower part of said chamber.

As shown, the tank is provided at one end with a suitable gate G for removing from the chamber the products collected therein by the separator. Said gate may be of any construction preferred by a skilled constructor. The gate is shown as hinged at g to a gate flange g' fixed to the end of the tank,

and when closed the gate is locked tightly against its seat on the flange g' by a suitable form of clamp g^2 .

- 10 The inclined grating e rests upon the floor of the tank, and the grating e' is positioned intermediate the door G and said inclined grating, the latter acting to feed the products by gravity to the horizontal grating e' so that the products are accumulated adjacent the door, thus making provision for the collection of the products within the chamber so that the products can be raked or otherwise removed from the chamber with ease and facility.
- 15 As shown, provision is made for the discharge of the hydraulic current away from the scow or barge, to which end an education pipe H is connected to the discharge side of the pump B , said pipe being supported at h .

20 I is a priming tank supported at i upon the scow or barge adjacent the pump B . This tank is adapted to contain the fluid for initially filling the pump, the collecting chamber, and the suction pipe so as to prime the excavator when starting it into service. Said priming tank is connected to the pump by a pipe j , the latter having a cock j' adapted to be opened and closed as required.

25 This being the construction of my hydraulic harvester, the operation is as follows:—Gate G is tightly closed; and valve j' is opened for liquid to flow from tank I into the pump, the collecting chamber, and the suction pipe in order to prime the same. The inclined length C' of the suction pipe is shifted as required in order to reach the bed, and pump B is set into action to establish and maintain a flow of liquid

30 through the suction pipe, the chamber and the pump, valve j' being closed and the flow of the current being carried off by the education pipe. The inflow of the hydraulic current set up in the suction pipe is sufficient to dislodge the products from the bed and to transport or convey the same within the suction pipe to the collecting chamber: the water flowing freely into said chamber, through the grating E and out of the chamber through the outlet d' . The products carried by the hydraulic current lodge against the grating e and are directed by the latter toward grating e' , whereby the products are collected within the chamber, being caught

35 by the separator and detained against escape with the hydraulic current through outlet d' . When it is desired to remove the products collected within the chamber, the pump B is stopped and gate G is opened, the accumulated mass being raked out of the chamber.

40 If deemed advisable, a plurality of collecting chambers may be used in connection with the hydraulic pump and a suitable arrangement of valved pipe connections to provide

45 for the continued operation of harvesting the products within one chamber while the other chamber is being emptied.

50 My hydraulic harvester enables the operation of dislodging the products, transporting the same, and separating said products from the hydraulic current to be carried on by a single agency, i. e., a hydraulic current, and, further, the collection of the products is effected without interrupting the flow of said hydraulic current, whereby the operation of harvesting submarine growths is performed rapidly and economically. The grating acts to detain the products within the collecting chamber in order to accumulate such products in a mass for subsequent removal, and to preclude the products from passing into the hydraulic pump, thus obviating the possibility of injury to the working elements of the hydraulic harvester.

55 Having thus fully described the invention, what I claim as new, and desire to secure by Letters Patent is:

60 1. In a dredging apparatus, a substantially closed chamber provided in an end wall thereof with a normally closed opening for the removal of the dredged material, a grate within the receptacle and inclined with respect to the plane of the normally closed opening, a second grate positioned intermediate the inclined grate and said opening, a pump connection in communication with the receptacle below said grates, and a suction pipe attached to the receptacle above the inclined grate and the second grate.

65 2. In a dredging apparatus, a substantially closed receptacle provided with a normally closed opening, a horizontal grate within the receptacle and contiguous to said opening, another grate also within the receptacle and inclined relatively to the horizontal grate, a pump connection in communication with said receptacle on one side of the grates, and a suction pipe communicating with the receptacle on the opposite side of the grates from said pump connection.

70 3. In an apparatus of the class described, a substantially closed receptacle provided with an inlet and an outlet for the flow of a hydraulic current, said receptacle having a separate normally closed outlet for the removal of material adapted to be accumulated within the receptacle, a separating grating positioned within the receptacle and intermediate said inlet and the outlet, said grating being inclined, and a relatively stationary second grating within the receptacle, said second grating being intermediate the normally closed outlet to contact with and form a part of the directing surface of the inclined grating.

75 4. In an apparatus of the class described, the combination of a closed collecting receptacle provided with an interiorly positioned

grating, a suction pipe connected with said receptacle, a hydraulic pump the intake of which is in communication with the face of said receptacle to draw fluid through the grate, a priming tank, and a valved connection between the priming tank and said pump whereby the pump, the closed receptacle and the suction pipe may be supplied with fluid from said tank for priming the apparatus and flushing the grate.

5. In an apparatus of the class described, a closed collecting chamber having an interiorly-positioned grating, a suction pipe connected with said chamber, a hydraulic pump the intake of which is in communication with said chamber to draw fluid through the grating, a second grating fixed relatively to said first-named grating to receive the material automatically therefrom, a normally closed outlet in the end of the chamber adjacent said second grating, said gratings

being disposed intermediate the suction inlet afforded by the suction pipe and the suction outlet constituted by the intake of said hydraulic pump.

6. In an apparatus of the class described, a closed collecting chamber having an interiorly-positioned grating, a suction pipe connected with said chamber, a hydraulic pump the intake of which is in communication with said chamber to draw fluid through the grating, said grating being disposed in a plane below that of the incoming fluid, a second grating fixed relatively to the first-named grating to automatically receive the material therefrom, a normally closed outlet in the end of the chamber adjacent said second grating, and a floatable structure on which said chamber is mounted.

In testimony whereof, I have hereto set my hand this 22nd day of March, 1920.

FRED FEAR.
